ELECTRIC SWITCH

Ami Cornu, La Chaux-de-Fonds, Switzerland

Application July 3, 1933, Serial No. 678,840
In Germany July 7, 1932

1 Claim. (Cl. 200—63)

The present invention relates to a switch of the ordinary well known rotary step by step type.

The main object of the invention is to provide 5 an improved quick action by making use of balls.

The nature and advantages of the invention will be better understood when the following detailed description is read in connection with the 10 accompanying drawings, the invention residing in the construction, combination and arrangement of parts as claimed.

In the drawings forming part of this application, like numerals of reference indicate similar 15 parts in the several views, and wherein:—

Fig. 1 is a sectional elevation of a switch;

Fig. 2 shows the base of the switch in a top view.

Fig. 3 illustrates in a top view the arrangement 20 of the balls.

Fig. 4 is a sectional elevation of a modified construction of the switch.

Fig. 5 is a top view of the switch shown in Fig. 4.

25 Figs. 6 and 7 show two different types of contracting members in side elevation.

Fig. 8 illustrates a third embodiment of my invention in sectional elevation.

Fig. 9 is a top view of the base of the switch 30 shown in Fig. 2.

Figs. 10 and 11 are top views of parts of the base.

Fig. 12 illustrates in a perspective view a detail of construction.

35 The switch shown in Figs. 1-3 comprises a base 1 for instance of ceramic material. In the base 1 contact members 2 are fixed concentrically arranged to a ring plate 4. The plate 4 is provided with a screw threaded bore 3 in which a bolt 5

40 having a flanged head 6 is screwed. Screws 7 engaging screw threaded recesses in the members 2 serve to clamp the wires. On the bolt 5 a plate 10 is rotatably mounted having a hub 8 of square cross-section. The hub 8 engages a square hole

45 of the contact member 9 which is slidably arranged on said hub. The contact member 9 consists of superposed leaves of springy sheet metal.

Between the head 10 and the contact member 9 a coiled spring 12 is arranged on said bolt 5; 50 the spring 12 presses the member 9 on to the terminals 2. Between the parts 4 and 10 two circular rows of steel balls 21, 22 are arranged.

The two rows are concentrically arranged to bolt 5 and have an equal number of balls. Each of 55 the balls 21 rests in a recess of plate 4 and each

of the balls 22 engages a notch in plate 10. The spring 12 keeps the balls 21, 22 in mutual engagement. The diameters of the two rows may be different and the balls 21, 22 may be of equal or of different size, provided that the balls of both rows are in contact with each other. In a circular groove of the base 1 a cup-shaped ring 13 is slidably mounted having at its inner face two grooves 14 running at right angles to each other adapted to receive the contact members 9. By turning the ring 13 the members 9 and therewith the hub 8 and the plate 10 with the balls 22 partake of the rotary motion. The balls 22 being forced to pass over the stationary balls 21 move the plate 10 and therewith the contact members 9 in axial direction against the action of spring 12. The members 2 and 9 are brought out of contact and the circuit is broken. By changing the diameters of the rows of balls and of the balls the amount of lift may be varied. The ring 13 is retained by a washer 15 and a screw 17 screwed into bolt 5. The upper face of the ring 13 is covered by a disk 19 which is removably held by an annular screw 18 secured on the ring 13 by a set screw 19'. The disk 19 may be of any suitable material, for instance of celluloid, and colour to make the switch to agree with the colour of the walls of the room. The disk 19 may be of glass and a piece of coloured paper may be interposed between the ring 13 and the disk 19. On the base 1 a ring 20 of coloured material for instance glass, celluloid or like material to match the switch to the wood or paint of paper hangings etc. of the wall.

To adapt the switch to any connection, the 90 screws 7' (Figs. 1 and 2) are provided with heads to hold contact members 28 (Fig. 2). Instead of contact members 28 the members 2 may be electrically connected by wires arranged in the hollow of the base 1.

To retain the parts 2 and 9 in their engaging 95 position they may be shaped as shown in Figs. 6 and 7. The one part either part 2^x (Fig. 6) or part 9^x (Fig. 7) is wedge shaped and engages correspondingly shaped recessed portion of the other member.

The switch shown in Figs. 4 and 5 differs from that shown in Figs. 1 and 2 mainly by the shape 100 of the casing 1^x. The latter is shaped to be inserted in a recess of the wall in such a manner that the square flange 26 may be arranged flush with the wall. The flange 26 is provided with bores 27 to receive the screws or the like to fasten the switch to the wall. The steel balls and their action are the same as described with reference 105 to Figs. 1 and 2. The disk 19^x is provided with 110

a central opening adapted to receive a hub 23 of the disk 13, by means of which the contact member 9^a is being rotated, in the manner described above with reference to Figs. 1 and 2.

5 The disk 13' is provided with grooves to receive the contact member 9^a. In the hub 23 the handle piece 24 is fixed by means of a screw bolt 25.

In the construction shown in Figures 8-11 the switch comprises a base 1^a in which sleeve like 10 contact members 2^a are arranged in a circular row concentric to the central pin 5^a, which is secured to the base by means of a screw threaded bolt 3^a and a nut screwed thereon. A plate 4^a fastened to the base 1^a is provided with a circular row of recesses adapted to receive each a steel ball 21^a which are arranged in a circular row concentric to the pin 5^a. On the pin 5^a the plate 29^a is slidably mounted having a circular row of notches, each adapted to receive 20 a steel ball 22^a. The balls 22^a rest on and between the balls 21^a. The plate 29^a is provided with a hub of square cross-section and is pressed down by the spring 12^a which abuts with one end on the plate 29^a and with the other end 25 on the flanged head 6^a of the pin 5^a.

On the hub 8^a a contact member 9^a is arranged; the free ends of said contact member 9^a are U-shaped. The springy ends of said member 9^a are arranged in the common conical plane 30 and said ends cooperate with the slanting faces of the members 2^a to which the wires of the circuit are fastened in the well known manner. The arms of the member 9^a rest within grooves 11^a of the plate 29^a and project into recesses 14^a 35 of the annular plate 30^a. The plate 30^a is provided with a groove 32 into which nuts 40 project, which nuts are screwed on bolts 39 located in the top plate 37. The plate 30^a on being turned takes the contact member 9^a with 40 it. Projections 31^a at the lower face of the plate 30^a engage the arms of the contact member 9^a. In the plate 30^a a groove 33 is provided in which a wire spring 34 is located. The free ends of 45 the spring 34 are bent outwardly, they project into a radial slot 35 of the plate 30^a. The free

ends are covered with short pieces 36 of rubber tubing.

To the top plate 37 the ring 18^a is fastened by means of screws 19^a projecting with their inner ends into notches 38 of the plate 30^a and 80 engaging slanting faces therein. By driving in said screws 19^a the ring 18^a is axially displaced and presses the disk 19^{xx} tightly on the top face of the plate 37. The latter is provided with a radial slot 42 to receive the free ends of the 85 spring 34.

By turning the ring 18^a the plate 37 is turned therewith. The spring 34 is tensioned until the friction between the parts 2^a and 9^a is overcome in which case the expanding spring will throw 90 the member 9^a for a quarter turn.

As shown in Fig. 11 the plate 37^{xx} is provided with an approximately square recess 43 adapted to receive a member 44 (Fig. 12) of corresponding shape. With the member 44 a handle 24^{xx} 95 is connected by a screw bolt 25^{xx}, the handle being placed in a slot of an extension 23^{xx} of the member 44.

The parts 18^a, 19^a, 24^a and 37 are rigidly connected while the plate 30^a is coupled with the 100 plate 37 by the square nuts 44 engaging the groove 32.

Having now particularly described and ascertained the nature of my said invention and in what manner the same is to be performed, I declare that what I claim is:

An electric switch comprising a base of insulating material, a manually operable rotary member, cooperating contact members on said base and on said rotary member, two superimposed circular rows of balls, one row being held by the stationary base and the other row being held by the rotary member, a spring to maintain the balls in engagement with each other, the said circular rows of balls having unequal diameters, 110 with the balls of the respective rows of different diameters, the balls of the two rows contacting each other.

AMI CORNU.
